UNITED STATES PATENT OFFICE.

HAROLD HODGSON, ROY HODGSON, AND JOHN GLAZBROOK, OF CHICAGO, ILLINOIS.

JUNCTION-BOARD.

1,139,764.

Specification of Letters Patent.

Patented May 18, 1915.

Application filed March 1, 1912. Serial No. 680,818.

To all whom it may concern:

Be it known that we, HAROLD HODGSON, ROY HODGSON, and JOHN GLAZBROOK, subjects of the King of England, and residents 5 of the city of Chicago, county of Cook, and State of Illinois, have invented certain new and useful Improvements in Junction-Boards, of which the following is a specification.

10 Our invention relates to junction boards, that is to devices designed for employment in connecting the terminals of wires at the junctures of line and branch circuits.

Our invention consists in a junction board 15 which is especially designed for use in the construction of sleeping cars in which each section may be provided with an electric fan, a center light and a head and foot light in each berth. In such sleeping cars there 20 are ordinarily four complete main circuits to accommodate such electric appliances, one circuit for the electric fans, one circuit for the center lights, one circuit for the lights in the upper berth and one circuit for the 25 lights in the lower berth. In the present construction branch circuits accommodating these appliances are joined to the main circuit at each section, by means of the conventional splice and solder and protected 30 with the usual insulating material. When it is necessary to test any particular branch circuit it is necessary to take the insulating material from the connection and sever the connection. With our device, a junction 35 board is placed in a convenient portion of the panel of such section, and the main circuit cut and connected by means of bus bars to which are connected the branch circuits as is fully described hereinafter.

40 The object of our invention is the production of a junction board of the character mentioned, which will be of improved construction and efficient in use.

Other objects will appear hereinafter.

45 Our invention will be best understood by reference to the accompanying drawing forming a part of this specification, and in which,

Figure 1 is a plan view of a junction 50 board embodying our invention, Fig. 2 is an end elevation thereof, and Fig. 3 is a section taken on line $\alpha\alpha$ of Fig. 1.

The preferred form of construction, as 55 illustrated in the drawing, comprises a board or body 1 which is formed of a suitable insulating material, such as fiber. The

board 1 is of rectangular form and is comparatively thin, one side thereof being formed with a plurality of spaced parallelly extending grooves 2. Arranged in the 60 grooves 2 are elongated rectangular metallic bus bars 3 of dimensions such as to adapt the same to snugly fit the grooves 2, said bars being of a length corresponding with that of the corresponding dimension of the 65 board 1. The bus bars 3 are secured in position in the grooves 2 by means of screws 4 which project therethrough adjacent the extremities of said bars into the board 1.

Provided at each extremity of each of the 70 bus bars 3 is a binding post for connection with the line circuit wires. Each of said binding posts consists of a threaded stud 5 upon which is threaded a binding nut 6 and a lock-nut 7, the latter serving, as will be understood, to secure the former in operative or binding position. Provided intermediate 75 the extremities of each of the bars 3 is a binding post, the intermediate binding posts being provided for connection with the 80 branch circuit wires. Each of the intermediate binding posts is of a construction identical with that of the terminal binding posts above described, the stud 5' and nuts 6' and 7' corresponding with the stud 5 and 85 nuts 6 and 7, respectively.

Provided upon the board 1 at the corners thereof, are short bars 8 embedded therein in the same manner as the bars 3, the bars 8 being secured in position by screws 9. 90 Upon each of the bars 8 is provided a binding post 10 which is of a construction the same as that of the terminal and intermediate binding posts of the bus bars just described. The binding posts 10 are provided 95 to accommodate the insertion of an individual switch, not shown, in each branch circuit. It is designed to lead one of the wires of each branch circuit from its binding post 5' to its corresponding fixture, 100 then to a binding post 10, then to the individual switch and finally back to the proper binding post 5' to complete the branch circuit. From this arrangement it will be seen that each fixture and its individual switch 105 may be tested separately from the junction board.

In use, the board 1 is secured in operative position by bolts, screws, or similar securing devices, the same being provided 110 with perforations 11 for the accommodation of said securing devices.

With a junction board of the construction set forth, it will be seen that the branch circuit wires will be connected with the line circuit wires in such a manner that disconnection thereof is rendered convenient and easy, this being effected by simply unscrewing the nuts 6' and 7', or the line wires themselves may be disconnected by unscrewing nuts 6 and 7.

10 In use, the bus bars 3 are divided into pairs and connected in the four main circuits by means of binding posts 5, in a manner, such, as reading from the left hand side of Figs. 1 and 2, the first and second bus bars 3 are connected in one main circuit, the third and fourth bus bars 3 are connected in another main circuit, the fifth and sixth bus bars are connected in another main circuit and the seventh and eighth bus bars are connected in the remaining main circuit. The branch circuits are connected to the corresponding main circuits by means of the binding post 5' as already explained. The four main circuits are provided so that a 25 separate main circuit will run through the car for the center lights, electric fans, lights for the upper berth and lights for the lower berth. This is desirable for the reason that 30 separate switches may be provided to control each main circuit. The branch circuits are each provided with an individual switch, as explained, so that each individual fixture may be cut out when so desired.

While we have illustrated and described the preferred form of construction for carrying our invention into effect, this is capable of variation and modification without departing from the spirit of the invention. We, therefore, do not wish to be limited to the exact details of construction set forth, 40 but desire to avail ourselves of such variations and modifications as come within the scope of the appended claim.

Having described our invention, what we claim as new and desire to secure by Letters Patent, is:

A device of the kind described comprising a base of insulating material having parallel grooves in one side thereof; a bus bar in and snugly fitting each of said grooves, the tops 50 of said base and bus bars being substantially co-planar; screws securing each bus bar to said base, and binding posts secured to and extending outwardly from said bus bars, there being one binding post at each end of 55 each bar, and one binding post intermediate the ends thereof, substantially as described.

In testimony whereof we have signed our names to this specification in the presence of two subscribing witnesses.

HAROLD HODGSON.
